UNITED STATES PATENT OFFICE.

SAMUEL R. SCOTTRON, OF BROOKLYN, NEW YORK.

POLE-TIP.

SPECIFICATION forming part of Letters Patent No. 349,525, dated September 21, 1886.

Application filed February 11, 1886. Serial No. 191,569. (No model.)

To all whom it may concern:

Be it known that I, SAMUEL R. SCOTTRON, a citizen of the United States, residing at Brooklyn, county of Kings, State of New York, have 5 invented certain new and useful Improvements in Pole-Tips, of which the following is a specification.

This invention relates to end ornaments for curtain-poles, or what are technically known 10 as "curtain-pole tips," and it consists of a piece of metal or other suitable material, made ornamental by embossing or other process, adapted to cover or hide the end of the pole by being retained in position at the side thereof. For this purpose the ornament is provided 15 with a clamping-ring which embraces the pole, and is held thereon by the resilience of the ring, or by a screw passed through its free ends, thus adapting the ring to firmly clasp 20 poles of different diameters, and securely hold the ornament in position. This ornamental tip, by being adjustable on the ends of curtain-poles, obviates the necessity of making the 25 poles of exact lengths to suit the width of windows, &c., as the end of the pole may be anywhere behind the ornament, so as to be hidden by it. The amount of adjustment is therefore determined by the length of the ornament.

My invention also contemplates supporting 30 the pole by means of these end ornaments or tips, which I accomplish by bending out the ends of the clamping-rings, and forming holes through them, so as to set the same over hooks or upwardly-projecting points or brackets secured to the frame or wall.

To describe my invention more particularly, I will now refer to the accompanying drawings, in which—

Figure 1 is a front view of my improved 40 curtain-pole ornament or tip. Fig. 2 is an end view showing the clamping device as an open spring-ring. Fig. 3 is a similar view showing the clamping device or ring provided with a tightening-screw. Fig. 4 is an end view 45 showing the open ring adapted to act as a support for the pole, and Fig. 5 is a plan view of Fig. 4.

In all the figures of the drawings, *a* represents a plain cylindrical curtain-pole, and *b* the 50 ornamental end or tip, which may be made of

any metal or other suitable material, carved, embossed, or figured in any desired manner. One end of the ornament *b* is provided with a clamping-ring, either forming a part thereof or connected thereto, which admits of the longitudinal and angular adjustment of the tip on the pole. In Figure 1 this clamping-ring is 55 simply an open elastic ring, *c*, which by its resilience embraces the pole *a* with sufficient grip to retain the ornament *b* in position, so as to cover or hide the end of the pole *a*. It is adapted to embrace poles of different sizes, thus avoiding the necessity of making the tips specially for each size of pole, and is free to slide longitudinally on the pole, thus providing 60 for adjustment as to length of completed pole, and saving the trouble of fitting the poles to suit special cases.

In some cases, where the ornament *b* is made of heavy material, it may be desirable to provide for more gripping or holding power than would be due to the open spring-ring. I then propose to form bent ends *c' c'* on the ring *c*, and clamp them together by means of the screw *d*, which turns freely in one of the bent ends 70 and works in a tapped hole in the other one. This form also has adjustability as to gripping 75 poles of different sizes, and as to the longitudinal position of the tip on the pole.

An end ornament or pole tip made according 80 to this invention may be utilized to support the pole by setting the bent ends *c' c'* of the ring *c* over a hook or upwardly-projecting pin or stud of a bracket. In Figs. 4 and 5 a cornice-hook, *e*, is represented, the end *e'* of 85 which passes through the holes formed in the bent ends *c' c'* of the ring *c*. This end *e'* is bent backward slightly from the vertical to provide for more securely holding the ring *c*, and the pole *a* resting therein, with its paraphernalia, 90 it being observed that by this arrangement and form of supporting-hook the greater the weight of the pole, &c., the more securely will the pole-tips be retained on the hooks.

End ornaments have heretofore been connected to poles or cornices, so as to be capable of occupying different positions thereon. English Patent No. 8,471 of 1840 shows such devices. This I do not broadly claim.

Having now described my invention, what I

claim, and desire to secure by Letters Patent, is—

1. An ornament for cylindrical curtain-poles provided with an adjustable clamping-ring, whereby the ornament is securely held in any desired angular position at or near the end of the pole at the side thereof.
2. The combination, with a curtain-pole tip provided with an adjustable clamping-ring adapted to grip a cylindrical pole and having perforated bent ends, of a supporting device provided with an upwardly-projecting stud or pin which passes through the bent ends of the clamping-ring.

3. In combination, a curtain-pole, pole-tips, each composed of a side ornament, and an adjustable clamping-ring having perforated bent ends, and supporting devices each provided with an inclined projecting pin or stud which passes through the bent ends of a clamping-ring.

In testimony whereof I have hereunto set my hand, at Chicago, county of Cook, State of Illinois, this 29th day of January, 1886.

SAMUEL R. SCOTTRON.
